[57] CLAIM

The ornamental design for a baby seat, as shown and described.

DESCRIPTION

FIG. 1 is a front right side perspective view of a baby seat, the phantom lines illustrating a possible seat belt assembly which could be used with the baby seat are for illustrative purposes only and form no part of the claimed design;

FIG. 2 is a top view of the baby seat of FIG. 1;

FIG. 3 is a front view of the baby seat of FIG. 1;

FIG. 4 is a back view of the baby seat of FIG. 1;

FIG. 5 is a bottom view of the baby seat of FIG. 1; and,

FIG. 6 is a right side view of the baby seat of FIG. 1, the left side being a mirror image.
